PHONOGRAPH TONE ARM

Melvin H. Boldt, Glenview, Ill., assignor to Zenith Radio
Corporation, a corporation of Delaware

Filed Aug. 27, 1962, Ser. No. 71,471

Term of patent 14 years

(Cl. D26—14)

FIG. 1

FIGURE 1 is a perspective view of my new design for a phonograph tone arm;

FIGURE 2 is a plan view thereof; and

FIGURE 3 is a side elevational view thereof.

The dominant features of my design reside in those portions of the drawing shown by means of full lines.

I claim:

The ornamental design for a phonograph tone arm, substantially as shown and described.
